CLAIM

I claim the ornamental design for a table, as shown and described.

DESCRIPTION

FIG. 1 is a perspective view of a table;

FIG. 2 is a top plan thereof;

FIG. 3 is a bottom plan thereof; and,

FIG. 4 is an elevational view thereof.

The elevational view in FIG. 4 shows a side of the table, but the view would be the same if the table were turned 120 degrees or 240 degrees from the illustrated position.
